US00D624603S

(12) United States Design Patent
Shigeta

(10) Patent No.: US D624,603 S
(45) Date of Patent: * Sep. 28, 2010

(54) PLAYING CARD

(76) Inventor: Yasushi Shigeta, 10-1 Kawarayamachi
2-chome, Chuo-ku, Osaka-shi (JP)
542-0066

() Term: 14 Years

(21) Appl. No.: 29/351,283

(22) Filed: Dec. 3, 2009

(51) LOC (9) Cl. 21-01

(52) U.S. Cl. D21/376

(58) Field of Classification Search D6/582;
D21/376-384; 273/292-295

See application file for complete search history.
